UNITED STATES PATENT OFFICE.

MAX RUBIN, OF NEW YORK, N. Y.

DESIGN FOR A GARMENT-FASTENER.

SPECIFICATION forming part of Design No. 28,245, dated February 1, 1898.

Application filed June 26, 1897. Serial No. 642,541. Term of patent 7 years.

To all whom it may concern:

Be it known that I, MAX RUBIN, a citizen of the United States, and a resident of the city of New York, in the county of New York 5 and State of New York, have invented a certain new and original Design for Garment-Fasteners, of which the following is a specification.

The leading feature of my design consists 10 of a main plate bent upward at the lower end to form a hook on one face of the plate and bent downward at the upper end on the opposite face of the plate, the downward bend terminating in an outwardly-extending spur, 15 and an intermediate plate having its lower end bent up to form a hook and extended to the spur on the downward bend of the main plate.

In the accompanying drawing, forming a 20 part of this specification, a perspective view of my new and original design for garment-fastener is shown.

A is the main plate. B is the lower hook of same.

C is the outwardly-extending spur, terminating the downward bend of the main plate. 25

D is the intermediate plate, the lower end bent upward to form the hook E and extended to meet the spur C.

Having described my invention, what I claim as new, and desire to secure by Letters 30 Patent, is—

The design for a garment-fastener, substantially as herein shown and described.

Signed at New York, in the county of New 35 York and State of New York, this 21st day of June, A. D. 1897.

MAX RUBIN.
